UNITED STATES PATENT OFFICE.

JOHN ALBERT SWINDELL, OF PITTSBURGH, PENNSYLVANIA.

HEATING-FURNACE.

1,127,315.

Specification of Letters Patent.

Patented Feb. 2, 1915.

Application filed July 30, 1914. Serial No. 854,094.

To all whom it may concern:

Be it known that I, JOHN ALBERT SWINDELL, a citizen of the United States, residing at Pittsburgh, Allegheny county, 5 Pennsylvania, have invented a new and useful Improvement in Heating-Furnaces, of which the following is a full, clear, and exact description, reference being had to the accompanying drawings, forming part of 10 this specification, in which—

Figure 1 is a horizontal section of a heating furnace embodying my invention; Fig. 2 is a longitudinal vertical section of the same; Fig. 3 is a horizontal section, partly 15 broken away, through one of the feeder bars; Fig. 4 is a section on the line IV—IV of Fig. 2; Fig. 5 is an end elevation showing the charging end of the furnace; Figs. 6 and 7 are detail views showing a portion 20 of one of the charging devices in two different positions; Fig. 8 is a section on the line VIII—VIII of Fig. 7; Fig. 9 is a sectional view showing one of the charging devices in still another position; Figs. 10 and 11 are 25 sections taken, respectively, on the lines X—X and XI—XI of Fig. 9; and Fig. 12 is a detail sectional view showing a modified arrangement for discharging the blank.

My invention has relation to heating furnaces and particularly to that class of furnaces known as "blank-heating furnaces", and which are designed for the heating of billets and other blanks.

The invention has particular relation to 35 means for feeding billets or blanks through the heating chamber of the furnace. It also provides means of this character which can be operated to effect an automatic discharge of the billets or blanks at the discharge end 40 of the furnace. It also provides means whereby the charging doors of the furnace may be automatically opened and closed in proper timed relation to the movements of the feeding mechanisms.

Referring to the accompanying drawings, 45 in which I have shown the preferred embodiment of my invention, the numeral 2 designates the wall of a heating furnace having the main heating chamber 3 and the 50 extension or preheating chamber 4. My invention is not limited in its application to any particular type of furnace, and that shown is for the purpose of illustration only. Reference to my Patent No. 1,094,611, 55 dated April 28, 1914, may be had for a

more complete description of this particular furnace.

In accordance with my invention, I provide one or more longitudinally extending and operating feeder members or bars 5, which extend continuously through the chambers 3 and 4, and which are designed to carry the billets or other blanks into the furnace through the charging openings 6, and to deliver them through the discharge 65 openings 7 at the discharge end. In the drawings, I have shown two of these feeder members or bars, arranged in parallel relation, but either one or any other desired number may be employed, according to the 70 particular furnace. Each of these members or bars preferably consists of a body portion of metal, such as cast iron, and having the surface covering 5^a of refractory material. They are preferably water-cooled 75 by having suitable passages or spaces therein for the circulation of water. In the drawings, I have shown water-circulating pipes 8, cast therein and having suitable circulating connections, such as indicated 80 at 9. These members work in longitudinal pits or troughs 10, in the floor of the furnace, which are preferably provided with metal linings 11, which may also be water-cooled, as indicated at 12.

Each of the members 5 is supported by and arranged to travel longitudinally upon a series of rollers 13, journaled in depending brackets 14 and arranged to travel on the floor portion of the lining 11. Each of 90 said members is also provided with a number of depending swinging yokes 15, pivoted to the under side thereof at 16, and having rollers 17 journaled at their lower ends. These rollers are also arranged to 95 travel on the floor portions of the linings 11. These yokes are of such length that when the feeder bars are in normal positions, with the upper surfaces of their refractory coverings 5^a somewhat below the 100 floor level of the heating chambers 3 and 4, they will assume oblique positions, as shown in Fig. 2. In these positions, they will be adjacent to or resting against shoulders or raised projections 18, formed on said floors, 105 with a depression 19 behind each projection. The members 5 may be reciprocated by any suitable motive means, as by connections 20 with hydraulic cylinders 21.

In operation, the billets or other blanks 110

(indicated at A in the drawings) are placed on the members 5, in spaced relation, and said members are then reciprocated by the action of the cylinders 21. When the feeding members are in the position indicated in Figs. 2, 4 and 6, the upper surfaces of the refractory coverings 5^a are slightly below the level of the floor of the heating chambers, so that the billets will be supported by their end portions only, which rest upon such floor. As each member 5 is moved forwardly, the rollers 17 on the yokes 16 will engage with the shoulders or projections 18 in a manner to prevent their rolling movement, and in this way are caused to exert a lifting action upon the members until such time as the centers 16 pass the centers of these rollers. This lifting movement raises the member 5 and the series of billets in the manner shown in Figs. 7 and 8, and also at the right-hand side of Fig. 4, and thereby gives the entire series of billets an advancing movement through the heating chambers. After the centers 16 pass the centers of the rollers 17, the yokes 15 will pass over the projections 18 into the depressions 19, as shown in Fig. 9, and the member 5 will fall to its former level. During the reverse stroke of the cylinder 21, the yokes 15 and rollers 17 trail freely over the projections 18 and back to their original positions in front of such projections. The billets are therefore left in their advanced positions during this idle return movement of the feeders.

As the billets successively come to the position indicated at A' in Fig. 2, the next forward movement of the feeder will carry the last billet over inclines 22, formed in the 40 floor of the heating chamber 3, at the discharge end thereof, and it will then roll down such inclines to the position indicated at A² in Fig. 2. The billet is now in a position to be engaged by the end portion 5^b of 45 the feeder upon its next forward stroke, this end portion being at a lower level. In this manner, the billet will be automatically pushed out through one of the discharge openings 7, and on to the usual carry-off rollers 23. The openings 7 may be closed by 50 pivoted outwardly swinging doors 24, capable of being pushed outwardly and upwardly by the billets to permit their successive discharge, and to swing back into closing position 55 after such discharge. I may, however, discharge the blanks in any other suitable manner. Thus, in Fig. 12, I have shown the feeder as arranged to carry the blanks entirely through the furnace, with inclines 22^a 60 arranged to discharge on to inclined ways or skids 22^b, which deliver the blanks to the carry-off rollers 23^a.

The charging openings 6 are preferably provided with the usual vertically sliding doors 25. I preferably provide means where-

by these doors will be automatically opened and closed in proper timed relation to the movements of the feeders. This may be accomplished in various ways. In the arrangement shown, each door has a connection 26 with a crank arm 27 of a rocker shaft 28, journaled in a suitable bracket 29, secured to the frame of the furnace at the charging end thereof. This shaft has other crank arms 30, and to each of these arms is connected the upper end of a link 31. The links 31 are connected at their lower ends to a transverse rod or shaft 32, which passes loosely through an elongated slot 33, in an extension of the body portion of the feeder 5, which projects through the charging opening. These transverse rods also project through vertically elongated slots 34, in the supports 35, at each side of such extension, and upon which supports the billets rest before being carried into the furnace.

It will be readily seen that as the feeders are reciprocated, the rods or shafts 32 will be actuated in a manner to cause the actuation of the rock shafts 28, to raise and lower the charging doors. 96

I may also provide means whereby, as the billets are operated in a step-by-step manner through the heating chambers, they will also be turned into different positions to thereby be more uniformly heated throughout. This may be readily accomplished by providing the floor of the heating chambers, adjacent to each of the feeders, with transversely toothed surfaces, such as indicated at 36 in Figs. 6 to 11. The billets when resting on the floor of the chambers rest in the depressions of the teeth in the manner shown in Fig. 6. When they are raised by the action of the feeders to the position shown in Fig. 7, they will be turned to horizontal position, and when again lowered, will take a different and partially turned position. In this manner, each billet may be completely turned any desired number of times in passing through the heating chambers 3 and 4. 100 105 110

The advantages of my invention are numerous. It provides feeding mechanism by which the billets can be kept in properly spaced relation during their entire travel through the furnace. At each operation of the feeders, the entire series of billets within the heating chambers are simultaneously moved forward and lowered without any substantial change in the spaced relation thereof. Therefore, by feeding the billets into the furnace at proper intervals, a proper spacing can be at all times maintained. This is of advantage, since it not only prevents any tendency of the billets to stick, but it keeps them spaced so that practically all surfaces of each billet are equally subjected to heating action. This uniformity of heating action is further obtained by the fact

that between the feeding intervals, the billets are supported by their end portions only, and there is a free circulation below them and between them and the upper surfaces 5 of the feeders.

My invention also obviates to a very great extent hard or black spots on the billets, such as commonly occur when they are pushed through a heating chamber on water- 10 cooled pipes or other supports.

I do not desire to limit myself to the particular construction and arrangement of parts which I have herein shown and described, as it will be obvious that various 15 changes can be made therein, without departing from the spirit and scope of my invention as defined in the appended claims. Thus any suitable motive means may be employed for effecting the reciprocating movement of the feeders, and the means for elevating the feeders as they are reciprocated forwardly may be changed, and various 20 other changes may be made.

I claim:

25 1. A heating furnace, having a longitudinally movable feeder, means for imparting a reciprocating movement to the feeder, and a lifting member, pivotally connected to the feeder and depending therefrom, the 30 furnace having a fulcrum portion for contact with said member; substantially as described.

35 2. A heating furnace having a longitudinally movable feeder, means for reciprocating the feeder, wheeled supports upon which the feeder is arranged to travel, and auxiliary supports which travel idly with the feeder at portions of its movement and upon which the feeder fulcrums at another portion 40 of its movement; substantially as described.

45 3. A heating furnace having a longitudinal trough in the floor of its heating chamber, a feeder movable longitudinally in said trough, motive means connected to the feeder, and a member pivotally connected to the feeder and arranged to travel on the floor of said trough, said floor having a fulcruming portion for said member; substantially 50 as described.

55 4. A heating furnace having a longitudinal trough in the floor of its heating chamber, a feeder movable in said trough, motive means for reciprocating the feeder, and pivoted supporting and lifting members carried by said feeder and also arranged to travel in said trough, the trough having fulcruming portions for engagement with said members; substantially as described.

60 5. A heating furnace having a longitudinal trough in the floor of its heating cham-

ber, a feeder movable in said trough, motive means for reciprocating the feeder, and pivoted supporting and lifting members carried by said feeder and also arranged to travel 65 in said trough, the trough having projections on its floor and recesses adjacent to said projections for co-action with said members; substantially as described.

6. A heating furnace having a trough in 70 the floor of its heating chamber, a feeder arranged to move in said trough and having rollers which travel on the bottom wall thereof, motive means for reciprocating the feeder, and means carried by said feeder and 75 coöperating with the trough to cause a rising and falling movement of the feeder during its reciprocation; substantially as described.

7. A heating furnace having a longitudinal trough, a feeder arranged to move in said trough, and motive means for reciprocating the feeder, a door movable vertically toward and away from the feeder, a shaft extending through a slotted opening in the outer end 85 portion of the feeder, and operating connections between said shaft and the door; substantially as described.

8. A heating furnace having a longitudinal trough in the floor of its heating chamber, a feeder movable longitudinally in said trough, motive means connected to the feeder, and a member pivotally connected to the feeder and arranged to travel on the floor of said trough, said floor having a fulcruming 95 portion for said member, together with means coöperating with the feeder for imparting a turning movement to the blanks; substantially as described.

9. A heating furnace having a longitudinally movable feeder, supports for said feeder both at its end and intermediate portions, means for reciprocating the feeder, and other supports which are operative only at certain portions of the movement, together with 105 means whereby said other supports effect a lifting movement of the bar; substantially as described.

10. A heating furnace having a trough in the floor of its heating chamber, a longitudinally movable feeder working in said trough, and blank-supporting surfaces at each side of the trough, said surfaces having projections for engaging and turning the blank, substantially as described. 110 115

In testimony whereof, I have hereunto set my hand.

JOHN ALBERT SWINDELL.
